UNITED STATES PATENT OFFICE.

HERBERT H. BUNKER, OF JERSEY CITY, NEW JERSEY, ASSIGNOR TO KERLOW STEEL FLOORING CO., OF JERSEY CITY, NEW JERSEY, A CORPORATION OF NEW JERSEY.

MULTIPLE-DIE MACHINE.

Application filed December 31, 1921. Serial No. 526,439.

To all whom it may concern:

Be it known that I, HERBERT H. BUNKER, a citizen of the United States, residing in Jersey City, county of Hudson, and State of New Jersey, have invented certain new and useful Improvements in Multiple-Die Machines, of which the following is a specification.

My invention relates to dies for bending or stamping a plurality of corrugations or bends in a work sheet or bar. The object of the present invention is to provide an improved device of the above class which shall be of simple construction and adapted to operate upon the work with less friction between the dies and work, less power required to operate the same, and less likelihood of unduly stretching the metal, and also to increase the life of the dies.

To these and other ends my invention consists in certain improvements and combination of parts as will be pointed out with greater particularity in the claims appended to this specification.

The drawing shows a side view of my apparatus at the completion of a bending operation.

In the reciprocal multiple die type of bending machines in which the metal travels or creeps inward to supply the additional surface required to make the grooves and angles of the mould, it has been found that when solid dies or those which cooperate with the full length of metal are used, that the friction between the dies and work is sufficient to cause undue stretching and often rupture of the work. Since in such case the metal does not creep inward enough to prevent stretching, these old forms require enormous pressure to bend the metal into the several corrugations. One suggested means of avoiding the above difficulty has been to make at least one of the die members in several parts and have first one of these to operate upon the work, and then another and so on. But such an expedient requires a more elaborate construction than my present invention which achieves substantially the same result with a simpler construction and yet without likelihood of injury to the metal.

In the drawing the numerals 10 and 11 indicate a pair of die holders which are reciprocable toward and from each other and adapted when spread apart to have a straight work piece inserted therebetween. In the

embodiment illustrated I have shown a plurality of main dies 12 and also a number of auxiliary dies 13, secured to each of the holding members 10 and 11 and around which the work 15 is adapted to be bent. In operation the substantially straight stock or work piece is inserted between the jaws of the machine, and as the jaws or die holders 10 and 11 move together, the length of the work contained within the machine increases to supply the added surface made necessary by the bends or corrugations. During the first part of the bending operation the work piece 15 is in contact with only a portion of the die members, i. e., the edges 12^a of the dies 12 are substantially the only parts of the dies which are in engagement with the work. For this reason the metal is subjected to less friction and is better able to travel inward from each end of the machine. As the jaws come together the edges 13^a of the dies 13 and portions 18 of the holders 10 and 11 also come into engagement with the work. It will be noticed however, that during no part of the bending operation is the entire work strip in contact with the dies and even at the end of the operation it will be seen that the portions 17 of the work are unsupported or free from frictional engagement with any of the dies. Thus my dies 13 may in general be termed skeleton dies. In the embodiment of my invention which is illustrated, the portions 16 of the work are the only parts which are clamped or cooperate on opposite sides with the dies.

For prolonging the life of the dies I have shown the members 12 and 13 as being secured by a bolt 14 or other appropriate means to enable each of the dies 12 and 13 to be reversed to compensate for wear and prolong their life. The edge 13^a of the die 13 is the portion of this die subjected to the most wear and when this die is shaped as illustrated I may subsequently reverse the die 13 and move the edge 13^b into the position now occupied by the edge 13^a, when the latter becomes worn, similarly the die 12 may be turned upside down to provide new edges 12^b when the operative edges 12^a become worn.

Among the advantages of my invention may be enumerated the freedom from friction caused by having portions of the work piece out of contact with the cooperating dies whereby the work is better enabled to

travel or creep inward and less power is required to operate the dies with a consequent lessened liability to undue stretching and rupture. Having portions of the 5 work always out of contact with any of the dies enables a simplified construction to be obtained at a reduced cost. During the latter part of the bending operation when the portion 16 of the work which was first of an 10 arcuate shape and is subsequently flattened as shown, there seems to be a slight movement of the metal in a direction different from its movement during the most part of the bending operation and in my invention 15 this later back lash or slight movement referred to is better taken care of and compensated for with less strain upon the jaws due to the unsupported portions 17 of the work. The simplicity of construction in 20 which all parts of the dies subjected to wear may be reversible or easily removable is an additional feature worthy of notice.

My dies are adapted to produce a precise and predetermined form for the finished 25 work, and in the embodiment illustrated the machine is adapted after the bending to produce a stamping operation; that is, one in which there is a slight flow or movement of some of the particles of the metal work 30 strip.

I claim:

1. A multiple skeleton die bending and stamping machine adapted to simultaneously form a plurality of corrugations in 35 a work strip and comprising a plurality of relatively reciprocable holding members, attached to each of said holding members being a plurality of dies over which the work is adapted to be shaped, said holding members on movement toward each other being adapted to first draw the work strip within 40 the machine from both ends in bending over the dies and then on further movement of the holding members to stamp portions 45 of the work strip in a number of places,

other portions of the work within the machine being out of contact with said dies.

2. A multiple skeleton die bending machine adapted to simultaneously form a plurality of corrugations in a work strip and comprising a pair of reciprocable holding members, attached to each of said reciprocable holding members being a plurality of dies over which the work is adapted to be shaped, said holding members on movement 50 toward each other being adapted to first draw the work strip within the machine in bending over the dies, the dies of one holding member being adapted on further movement of the holding members to co-operate 55 with opposite portions of the other holding member to clamp the work between them to insure a predetermined form of the work strip while a portion of the work strip within the machine is out of contact with 60 said dies and holding members.

3. A multiple skeleton die bending machine adapted to simultaneously form a number of corrugations in a metal work strip and comprising a plurality of relatively reciprocable holding members, a plurality of dies being attached to the holding members and over which the work is adapted to be drawn within the machine in bending, both of said holding members being 70 provided with a plurality of major dies and a number of auxiliary dies, a pair of said auxiliary dies on one holding member being arranged to co-operate with a major die on the opposite holding member to produce 75 a stamping operation and sharp angled bends on further movement of the holding members toward each other, the work strip being out of contact with said dies and holding members in a number of places within 80 the machine.

In testimony whereof, I have affixed my signature to this specification.

HERBERT H. BUNKER.
